[57] CLAIM

The ornamental designs for a multi-cone earplug, as shown and described.

DESCRIPTION

FIG. 1 is a front and bottom isometric view of a multi-cone earplug showing my new design;

FIG. 2 is a left side elevation view thereof, the right side being a mirror image thereof;

FIG. 3 is a front elevation view thereof;

FIG. 4 is a rear elevation view thereof;

FIG. 5 is a front and bottom isometric view of a multi-cone earplug showing another embodiment of my new design;

FIG. 6 is a left side elevation view of the earplug of FIG. 5, the right side being a mirror image thereof;

FIG. 7 is a front elevation view of the earplug of FIG. 5; and,

FIG. 8 is a rear elevation view of the earplug of FIG. 5.
